 Weston Electrical Instrument Corporation,
 Newark, N. J., a corporation of New Jersey

Application June 21, 1946, Serial No. 678,234

11 Claims. (Cl. 175—320)

1

This invention relates to relay apparatus and in particular to instrument type relays which control a load circuit in a desired manner in accordance with variation of the control current applied to the moving system of the instrument.

There are many different types of electrical apparatus which require that the power circuit thereto be controlled in accordance with variation of a related control current between predetermined upper and lower limits. As an example it may be required that the power circuit to the apparatus be closed when the control current reaches the predetermined low value and remain closed until the current has reached the predetermined high limit, or vice versa. Thus in an electric furnace having a thermo couple type of heat regulator, the minute current output of the thermo couple may be applied to the moving system of an instrument type relay so that as the temperature of the furnace falls below the selected operating point, one set of contacts are closed within the instrument which effects a closure of the furnace power supply circuit. As the furnace heat increases, the current output of the thermo couple increases causing the moving system of the instrument to close another set of contacts which effects an opening of the power circuit.

When using instrument type relays having magnetized contacts that require separation by means additional to the reverse torque of the instrument's moving system, the control has been found very reliable. Relay apparatus of this type may be found described in U. S. Patents Nos. 2,014,385; 2,014,386 and 2,014,387 issued September 17, 1935 to Anthony H. Lamb.

Each of these patents disclose a high-low control in which the load circuit is opened or closed as the control current through the instrument reaches predetermined high and low limits.

It is the general object of this invention to provide a simple, compact and relatively inexpensive arrangement for resetting the contacts of an instrument relay of the magnetic contact type.

A more specific object is to provide a high-low relay apparatus of the general type described which comprises alternately energized solenoids that actuate pusher means for resetting the high and low instrument contacts, and a transfer switch actuated in timed relation to operation of the solenoids to deenergize each of the latter after it has performed its contact resetting function and also to simultaneously ready the energizing circuit to the other solenoid.

2

Another specific object is to provide a pair of instrument relays of the magnetized contact type that are used to provide "on" and "off" control of a load circuit in accordance with variation in control current applied to the moving system of each relay between predetermined high and low limits, the contact resetting or separating means for the instruments being actuated by solenoids that are alternately energized to perform their function, and which are immediately thereafter deenergized by means of a transfer switch which operates in timed relation to the separation of the contacts to open the circuit to the last energized solenoid and to close a switch in the energizing circuit of the solenoid next to be energized by one of the sets of relay contacts.

Still another specific object is to provide an instrument relay of the magnetized contact type having one contact movable between a pair of stationary contacts, and a pair of solenoids for resetting or separating the contacts subsequent to their engagement, the circuit to each solenoid being controlled through the contacts of the instrument and also through contacts on a transfer switch which functions to deenergize each solenoid after it has performed its contact separating function and also to open and close the load circuit by means of contacts placed on the switch.

50 The foregoing and other objects and advantages of the invention will become more apparent from the following description when considered with the accompanying drawings in which preferred embodiments are shown.

55 Fig. 1 is a diagrammatic view of a relay instrument incorporating the invention having separate pointers which are magnetically attractive to corresponding "high" and "low" stationary contacts. Each of these pointers is provided 40 with a solenoid operated contact reset mechanism that is actuated when the other pointer engages its stationary contact, and a transfer switch is commonly operated by both reset mechanisms to obtain the desired reset sequence and solenoid deenergization;

50 Fig. 2 shows a modified arrangement of basically the same construction but using separate relay instruments, the necessary operating interrelationship between the reset mechanisms of the two instruments being obtained by an external relay which also controls the load circuit; and

55 Figs. 3 and 4 show still other modified forms of the invention wherein the instrument relay contains but a single moving system including

a pointer carried contact movable between "low" and "high" stationary contacts.

Referring now to Fig. 1, the relay includes a case 1 which houses a pair of instrument mechanisms 2 and 3. The left instrument mechanism 2 or "low" relay, as it is designated on the drawing, comprises a moving coil 4 that carries an electrically conductive pointer or contactor arm 5 on which a small iron rider 6 is fixed. Rider 6 constitutes the movable contact of the instrument and cooperates with a stationary, magnetized contact 7 that is made in the form of a small permanent magnet. Coil 4 may be connected, for example, across a control device (not shown) such as a thermocouple, photoelectric cell or some other device having a small but variable current output upon which the control is based. A permanent magnetic field is set up by a horseshoe type of magnet, only the poles 8, of which are shown. Hence as control current through coil 4 increases, pointer 5 will sweep clockwise in proportion to the magnitude of this current. Fig. 1 shows magnet contact 7 so placed in the sweep path of pointer 5 that the iron rider 6 will be drawn into engagement with contact 7 at a selected and relatively low magnitude of current in coil 4. The magnetic force holding rider 6 to contact 7 is greater than any torque developed by coil 4.

In order to "reset" the pointer 5, a pusher arm 9 in the form of a bell crank lever is supported on the casing 1 for rotation around pivot 10, the arm 9 moving in a plane adjacent to and parallel with the plane in which pointer 5 moves. One end of lever 9 terminates in a pin 11 which projects into the path of movement of pointer 5 and is adapted to push against the pointer and "reset" it by moving it just outside of the field of magnetic attraction between contact 7 and rider 6. The other end 12 of lever 9 is adapted to be acted upon by the armature 13 of a solenoid 14 when its coil 15 is energized. Thus as armature 13 is pulled up, lever 9 is rotated counter clockwise through a small distance to "reset" contactor arm 5.

The parts in the right instrument mechanism 3 or "high" relay as it is designated on the drawing have the same construction as those in instrument mechanism 2 and hence will not be described in detail. However, corresponding parts of the two instrument mechanisms have been given the same reference numerals but with primes added to the numerals on mechanism 3 for identification purposes. It is to be noted that magnet contact 7' is so placed in the sweep path of instrument pointer 5' that rider 6' will be drawn into engagement with contact 7' at a selected and relatively high magnitude of control current in coil 4'.

While the drawing shows riders 6, 6' as being of magnetic material and stationary contacts 7, 7' as magnet bodies, it will be understood that the same desired magnetic attraction can be obtained when the parts are reversed. Further, while it is preferred to use riders 6, 6' and contacts 7, 7' also as current carrying bodies, separate contacts for control circuit current only could be used.

Coils 4, 4' may be connected in series as shown to the source of control current that determines the operation of the load circuit as will be hereinafter explained, or they may be connected in other ways such as in parallel.

The functional arrangement of the parts in the "low" and "high" instrument mechanisms is

such that when "low" contact is made, the pointer arm 5' of the "high" instrument mechanism is reset, and vice versa. For performing this function, the relay instrument is provided with a transfer switch mechanism 16 that includes a contactor arm 17 mounted for movement about point 18 as a pivot. Arm 17 carries a rider 20 of soft iron or other magnetic material that moves between two stationary magnet contacts 19, 19'. The transfer switch 16 also includes a pair of pusher arms 22, 22' in the form of bell crank levers which throw arm 17 from one to the other of contacts 19, 19' in timed relation with the operation of solenoids 14, 14'. Accordingly, one end of each lever 22, 22' is provided with a pin 23, 23' which projects into the path of and engages contactor arm 17 while the other ends 24, 24' of each lever are so deposited as to be acted upon by the armatures 13, 13' respectively of solenoids 14 and 14' when their windings 15, 15' are energized.

Beginning with one side of battery 26, the electrical wiring of the instrument includes a conductor 27 leading to a connection on the electrically conductive pointers 5 and 5', a conductor 28 between contact 7 and one side of solenoid coil 15' and a conductor 29 between contact 7' and one side of solenoid coil 15. Contacts 19, 19' are connected by conductors 30 and 31, respectively to the other sides of solenoid coils 15' and 15; one side 32 of the load circuit is also connected to contact 7', and the other side 33 is connected to the other side of battery 26 as is also conductor 34 to contactor arm 17 of the transfer switch 16.

It will now be evident that the pointers 5, 5', their cooperating stationary contacts 7, 7', solenoids 14, 14' and transfer switch 16 are electrically and mechanically cross connected in such manner that whenever the pointer that is "free" is attracted to its associated magnet contact by reason of a change in control through its associated moving coil, and held there, the other pointer then being held to its magnet contact will be "reset" by its pusher arm and hence freed to ready it for the succeeding change in current through its moving coil in a reverse direction. This will be clear from an inspection of Fig. 1 where the parts are shown with pointer 5 held to contact 7, both solenoids 14, 14' are de-energized, contactor arm 17 of transfer switch 16 is held to magnet contact 19' and pointer 5' is moving clockwise in response to control current through moving coil 4' which, at this instant in the control current cycle is on the increase. When this current has increased to the "high" value preselected for load circuit operation, rider 6' on contactor arm 5' will then have moved into the field of attraction of magnet contact 7' and the two will then be drawn quickly and firmly into engagement. When this occurs, the voltage of the battery 26 is applied to the load circuit conductors 32, 33 to thereby furnish electrical power to a load, not shown. Simultaneously, a circuit for energizing coil 15 of solenoid 14 is completed from battery 26 through conductor 34, contactor arm 17 of transfer switch 16, contact 19', conductors 31, 29, contact 7' pointer 5' and conductor 27. Armature 13 of solenoid 14 is then pulled up, rotating pusher arm 9 counterclockwise to "reset" the "low" contact pointer 5, and also rotating pusher arm 22 clockwise to throw rider 20 on contactor arm 17 from contact 19' to contact 19. The dimensions of pusher arms 9 and 22 and their spatial positions relative to pointer 5 and

contactor arm 17 are such that when "high" contact is made, the pointer arm 5' of the "high" instrument mechanism is reset, and vice versa. For performing this function, the relay instrument is provided with a transfer switch mechanism 16 that includes a contactor arm 17 mounted for movement about point 18 as a pivot. Arm 17 carries a rider 20 of soft iron or other magnetic material that moves between two stationary magnet contacts 19, 19'. The transfer switch 16 also includes a pair of pusher arms 22, 22' in the form of bell crank levers which throw arm 17 from one to the other of contacts 19, 19' in timed relation with the operation of solenoids 14, 14'. Accordingly, one end of each lever 22, 22' is provided with a pin 23, 23' which projects into the path of and engages contactor arm 17 while the other ends 24, 24' of each lever are so deposited as to be acted upon by the armatures 13, 13' respectively of solenoids 14 and 14' when their windings 15, 15' are energized.

transfer switch arm 17 are so chosen that pointer 8 is reset in advance of movement of arm 17. As rider 20 breaks with contact 19', the circuit to coil 15 is opened and armature 13 then drops out.

The load circuit will now remain in the "energized" condition until the control current in coil 4 decreases to the selected "low" value whereupon rider 8 and contact 7 are drawn into engagement. Coil 15' of solenoid 14' is now energized for a brief period, armature 13' pulls up and rotates pusher arms 8' and 22' to first reset the pointer 5' and then transfer rider 20 on contactor arm 17 back to engagement with contact 19'. When pointer 5' is reset, the load circuit is broken, disconnecting the battery 26 therefrom, and the load circuit and relay then remain in this condition until the control current in coil 4' shall again have risen to the selected "high" value at which time rider 8' and contact 7' again engage and reconnect battery 26 to the load.

Summarizing the operation, increase in control current in coil 4' to a preselected magnitude operates the relay in one direction to connect battery 26, or some other source of power, to the load circuit conductors; the load circuit then remains in the "energized" condition until control current through coil 4 has decreased to a preselected magnitude whereupon the relay again operates, but in the reverse direction to disconnect battery 26 from the load conductors. By means of this improved relay action, cyclic "on" and "off" operation of a load circuit is obtained in accordance with cyclic variation in control current between selected maximum and minimum magnitudes. The arrangement is positive in action and has the further advantage in that the relay expends no energy except during the brief periods when it operates. Further by transferring the load conductor 32 to the contact 7, the load circuit shown or a second load circuit, if desired, could be closed when the control current in coil 4 reaches the selected "low" value and opened when the current in coil 4' reaches the selected "high" value.

Reference is now made to Fig. 2, in which a different instrument and transfer switch arrangement is used. In this arrangement, separate instruments in different casings are used, and the transfer switch is located externally of the instrument casings. Thus in Fig. 2, it is seen that the resetting solenoids 35, 35' actuate only the pusher arms 36, 36' which alternately reset pointers 37 and 37'. The transfer switch for selecting the correct reset mechanism is in the form of an auxiliary relay 38, energization of which is controlled in accordance with movement of the instrument pointers. In the illustrated embodiment, when current through coil 41' increases and the "high" contact is made, i. e. engagement between magnetic rider 38' and magnet contact 40', a circuit is completed from battery 42 through pointer 37' and conductors 43, 44 to reset solenoid 35, the return path from solenoid 35 to the battery being through conductor 45, relay contact 46, blade 47 and conductor 48. When the armature 48 of reset solenoid 35 pulls up, it rotates pusher arm 36 counterclockwise to reset the "low" pointer 37. The auxiliary power relay 38 is also energized from battery 42 upon engagement between rider 38' and contact 40' over conductors 43 and 48, but this relay has a slower operating characteristic than reset solenoids 35, 35' and hence solenoid 35 will have been energized and pointer 37 reset before relay

contact 46 and blade 47 are separated to open the circuit to solenoid 35.

When auxiliary relay 38 pulls in, blade 47 is transferred to relay contact 52 so as to ready the "high" contact reset solenoid 35' for energization as soon as the "low" pointer 37 moves back into engagement with contact 40 upon a selected decrease in control current. Relay 38 then remains in an energized state until the "low" contact is next made and hence the load circuit controlled by blade 53 and contact 54 of relay 38 likewise remains closed during this period.

As the control current through coil 41 decreases to the selected "low" value and rider 38 engages magnet contact 40, reset solenoid 35' is energized from battery 42 over conductors 55, 56, relay contact 52, blade 47 and conductor 48 to reset instrument pointer 37'. As rider 38' and contact 40' separate, solenoid 35 is deenergized and the load circuit is opened as blade 53 and contact 54 separate. Blade 47 moves to engage contact 46 and hence close the energizing circuit to solenoid 35 at this point whereupon solenoid 35 is "readied" for operation as soon as rider 38' and contact 40' next engage.

Reference is now made to Fig. 3 wherein the invention is embodied in an instrument relay having but a single moving system comprising coil 60, pointer arm 61 of electrically conductive material, and rider 62 of magnetic material. The pointer 61 operates between "low" and "high" stationary contacts 63, 63' of magnetized material in accordance with variation in control current through coil 60.

For resetting pointer arm 61, the instrument is provided with a reset mechanism comprised of inverted T arm 64 pivotally supported at 65. A pair of spaced insulating sleeves 66, 66' are mounted at the bottom of T arm 64. These extend to either side of pointer 61 and are so related to the pointer that when arm 64 is rocked to the right, it will reset the instrument pointer from the "low" contact 63 and when rocked to the left will reset the pointer from the "high" contact 63'. Arm 64 also carries a soft iron rider 67 which, as the arm rocks about its support pivot, is drawn firmly into engagement with either of two magnetized contacts 68 and 68'.

"Low" and "high" reset solenoids 69, 69' are included in the instrument. Their armatures are bell cranks 70 and 70' which are pivoted at 71, 71', and include end pins 72, 72' that are adapted to engage and rock T arm 64 back and forth as the windings of solenoids 69, 69' are alternately energized.

Wiring of the instrument includes conductors 73, 74 between the coil of solenoid 69 and magnetized contacts 63, 63'; conductors 75, 76 between the coil of solenoid 69' and magnetized contacts 63', 63'; a conductor 77 from one side of battery 78 to pointer 61; and a conductor 79 from the other side of battery 78 to reset arm 64.

The load device (not shown) controlled by the relay may be connected thereto by conductors 80, 81 if the battery 78 is also to be used as the source of power for the load. If the controlled load circuit is to be independent of the relay battery, the arrangement shown in Fig. 4 may be used in which the load circuit conductors are opened and closed at the set of contacts 67, 68'. The arrangement in Fig. 4 is like that of Fig. 3 in all other respects and hence need not be described.

Operation of the Fig. 3 type of instrument from a viewpoint of function is the same as those shown

in Figs. 1 and 2 in that the load circuit is placed in one condition as the "low" contact is made by the instrument pointer mechanism and remains in such condition until the "high" contact is made whereupon it is switched to another condition and remains in the latter condition until the "low" contact is again made.

In Fig. 3, the relay is shown in the condition where control current through coil 60 is increasing. At this time the load circuit is closed by contact between rider 67 on reset arm 64 and magnetized contact 68'. When the control current has attained the selected "high" magnitude, rider 62 on pointer 61 will be drawn into engagement with contact 68'. This completes the circuit from battery 78 to reset solenoid 68' causing bell crank armature 78' to rotate clockwise and rock arm 64 to the left moving it a sufficient distance for the rider 67 to be attracted to magnetized contact 68. During this movement, insulating sleeve 68' engages and resets pointer 61 from the "high" contact 68'. Solenoid 68' reverts to its deenergized state as rider 67 and contact 68' separate, the load circuit also being opened at this time.

Pointer 61 is now held away from contact 68', but upon a decrease in control current to the selected "low" value the pointer is then drawn into engagement with the low magnet contact 68. When this occurs, reset solenoid 68 is then momentarily energized to reset pointer 61, rock arm 64 to the right hand position and again close the load circuit which will remain in this condition until the control current through coil 60 is again sufficient to move pointer 61 far enough to the right so that engagement between rider 62 and contact 68' again occurs.

In conclusion, it will be evident that the several illustrated embodiments of the invention are indicative of a wide latitude of possible arrangements. Hence it is to be understood that the invention is not to be restricted to the specific embodiments shown, and that various changes may be made by those skilled in the art without departing from the spirit and scope of the invention as defined in the appended claims.

I claim:

1. A control device comprising an instrument adapted to respond to control current, said instrument having movable contact means adapted to move into engagement with separate stationary contact means at predetermined low and high values of control current respectively, said movable and stationary contacts being mutually magnetically attractive to assure firm engagement therebetween, a pair of solenoids, a pair of pusher arms, each said arm being controlled by one of said solenoids to separate said movable contact means from one of said stationary contact means, a two-position transfer switch including a blade contact movable between spaced stationary contacts, an energizing circuit for each solenoid including an instrument switch comprising said movable contact means and one of said stationary contact means, each energizing circuit also including the blade contact and one of the stationary contacts of said transfer switch, and means actuating said transfer switch to alternate positions to open the circuit of the last energized solenoid and to close its blade means upon the stationary contact thereof in the circuit of the other solenoid.

2. A control device as defined in claim 1 wherein said transfer switch actuating means com-

prises additional pusher arms actuated by each solenoid.

3. A control device as defined in claim 1 wherein said transfer switch includes load circuit contacts and the switch actuating means comprises a solenoid energized upon engagement between the movable contact means of said instrument and one of its associated stationary contact means.

10 4. A relay system comprising a pair of relays for measuring the value of a factor, one relay having magnetic contacts adapted to close when the measured value exceeds a predetermined value and the other relay having magnetic contacts adapted to close when the measured value falls below a predetermined value, a solenoid for each relay, pusher means actuated by each solenoid to separate the contacts of its associated relay, an energizing circuit for each solenoid, the circuit for one solenoid being completed upon engagement of the set of relay contacts separated by the other solenoid and vice versa.

15 transfer switch means including a transfer switch in each of said circuits, and means actuating said transfer switch means to open the circuit to each solenoid subsequent to operation of the pusher means actuated thereby and to close the transfer switch in the circuit of the other solenoid.

20 5. A control device comprising an instrument having a pair of moving systems adapted to respond to control current, a set of stationary and movable magnetically attractive contacts associated with each system, the movable contact of one contact set being adapted to be drawn into engagement with its associated stationary contact at a predetermined low value of control current and the movable contact of the other contact set being adapted to be drawn into engagement with its associated stationary contact at a predetermined high value of control current, a pair of alternately energized solenoids, an energizing circuit for each solenoid, the circuit for one solenoid being completed upon engagement of the set of contacts separated by the other solenoid and vice versa, a two position transfer switch, a pair of pusher arms actuated by each solenoid when energized, one arm of each pair being adapted to separate the contacts of one contact set and the other arm being adapted to trip said transfer switch, and means connecting said transfer switch into both said energizing circuits in such manner that when tripped by one solenoid, the energizing circuit to such

25 solenoid is interrupted and a gap in the energizing circuit to the other solenoid is closed.

30 6. A control device as defined in claim 5 wherein said transfer switch comprises a pivotally mounted switch arm rocked to alternate positions by said pusher arms, and said switch arm carries a contact movable between stationary contacts, said contacts being magnetized to assure firm engagement therebetween.

35 7. A control device comprising an instrument having a pair of moving systems adapted to respond to control current, a set of stationary and movable magnetically attractive contacts associated with each system, the movable contact of one contact set being adapted to be drawn into engagement with its associated stationary contact at a predetermined low value of control current and the movable contact of the other contact set being adapted to be drawn into engagement with its associated stationary contact at a predetermined high value of control current,

40 8. A control device as defined in claim 5 wherein said transfer switch comprises a pivotally mounted switch arm rocked to alternate positions by said pusher arms, and said switch arm carries a contact movable between stationary contacts, said contacts being magnetized to assure firm engagement therebetween.

45 9. A control device comprising an instrument having a pair of moving systems adapted to respond to control current, a set of stationary and movable magnetically attractive contacts associated with each system, the movable contact of one contact set being adapted to be drawn into engagement with its associated stationary contact at a predetermined low value of control current and the movable contact of the other contact set being adapted to be drawn into engagement with its associated stationary contact at a predetermined high value of control current,

a pair of alternately energized solenoids, pusher means actuated by each solenoid to separate the contacts of the associated contact set, an energizing circuit for each solenoid, the circuit for one solenoid being completed upon engagement of the set of contacts separated by the other solenoid and vice versa, and a solenoid operated combined transfer and load circuit switch having its operating coil connected in one of said solenoid energizing circuits, said switch including load circuit contacts and a second set of contacts controlling switching gaps in the respective solenoid energizing circuits and arranged upon actuation of the switch to open the energizing circuit to the solenoid last energized and to close a gap in the circuit to the solenoid next to be energized.

8. A control device comprising an instrument having a pointer carrying a contact and movable between a pair of stationary contacts, said pointer and stationary contacts being mutually attractive magnetically to insure firm engagement therebetween, a pair of solenoids, a pair of pusher arms, each said arm being actuated by one of the solenoids to effect separation of the contact on said pointer from one of said stationary contacts, a two-position transfer switch, and an energizing circuit for each solenoid, each said circuit being completed through said transfer switch upon engagement between the contact on said pointer and one of said stationary contacts, and said transfer switch being actuated to alternate positions by said pusher arms to open the circuit of each solenoid upon separation of the contacts whose engagement completed the circuit to that solenoid and close a switching gap in the energizing circuit of the other solenoid.

9. A control device comprising an instrument having a pointer carrying a contact and movable between a pair of stationary contacts, said

pointer and stationary contacts being mutually attractive magnetically to insure firm engagement therebetween, a rocker arm, said arm being pivotally mounted at one end and including a pair of spaced pins at the other end projecting into the path of movement of said pointer on each side thereof, a pair of pushers actuated respectively by said solenoids to rock said arm in opposite directions and separate the contacts on said pointer from each of the respective stationary contacts, a two-position transfer switch, and an energizing circuit for each said solenoid, each said circuit being completed through said transfer switch upon engagement between the contact on said pointer and one of said stationary contacts, and said transfer switch being actuated to alternate positions by said pusher arms to open the circuit of each solenoid upon separation of the contacts whose engagement completed the circuit to that solenoid and to close a switching gap in the energizing circuit of the other solenoid.

10. A control device as defined in claim 9 wherein said transfer switch comprises a contact on said rocker arm movable between a pair of stationary contacts, and the energizing circuit to each solenoid is connected through the movable switch contact and one of the stationary switch contacts.

11. A control device as defined in claim 9 wherein said transfer switch comprises a contact on said rocker arm movable between a pair of stationary contacts, and the energizing circuit to each solenoid is connected through the movable switch contact and one of the stationary switch contacts, said movable and stationary switch contacts being mutually attractive magnetically to assure firm engagement therebetween.

ELMER G. DE MOTT.
